UNITED STATES PATENT OFFICE.

CHARLES MAGEE McBRIDE AND FREDRICK JOHN HEYBACH, OF SAVANNAH,
GEORGIA.

WIRE-CRIMPING MACHINE.

SPECIFICATION forming part of Letters Patent No. 651,200, dated June 5, 1900.

Application filed November 6, 1899. Serial No. 735,990. (No model.)

To all whom it may concern:

Be it known that we, CHARLES MAGEE McBRIDE and FREDRICK JOHN HEYBACH, citizens of the United States, and residents of 5 Savannah, in the county of Chatham and State of Georgia, have invented a new and Improved Wire-Crimping Machine, of which the following is a full, clear, and exact description.

10 This invention relates to improvements in machines for crimping or forming bends in wires used particularly for fastening and supporting coiled springs in mattresses. These wires are usually formed by handwork, which 15 requires considerable time, and consequently an increased expense.

The object of our invention, therefore, is to provide a machine by means of which the wires may be rapidly and accurately formed 20 and cut off in proper lengths ready to be attached to the springs and frame, thus reducing the amount of labor and reducing the expense of production.

We will describe a wire-crimping machine 25 embodying our invention, and then point out the novel features in the appended claims.

Reference is to be had to the accompanying drawings, forming a part of this specification, in which similar characters of reference indicate corresponding parts in all the figures.

Figure 1 is a side elevation of a wire-crimping machine embodying our invention. Fig. 2 is a side elevation opposite to that of Fig. 1. Figs. 3, 4, 5, and 6 are fragmentary views showing different positions of the crimping die. Figs. 7 and 8 are fragmentary views showing different positions of the cutting and end-turning devices. Fig. 9 is a plan view thereof. Fig. 10 is a section on the line 10 10 of Fig. 8. Fig. 11 is a section on the line 11 11 of Fig. 7. Fig. 12 is an end view showing the driving mechanism. Fig. 13 is a section on the line 13 13 of Fig. 1. Fig. 14 is a fragmentary view showing a dog for imparting an intermittent motion to the machine. Fig. 15 is a section on the line 15 15 of Fig. 1, and Fig. 16 illustrates one of the wires as formed.

The frame of the machine comprises up- 50 rights 12, extended from a base 3, from which

uprights 4 also extend, and in these uprights 4 a wire-reel 5 has its journal-bearings.

Mounted to move vertically in guides 6, secured to one of the uprights 2, is a die carrier or plunger 7, to the lower end of which a die 8 is attached, which, coacting with the lower die 9, attached to the upright 2, forms the crimps or depressions 10 in the wire, as will be hereinafter described. Mounted to swing on the upright 2, at opposite sides of the die 9, are guides 11 12 for the wire as it is received from the reel, said wire being fed by means of a wheel 13, which may have a groove in its periphery to receive the wire, and a bearing-wheel 14. This bearing-wheel 14 has its shaft-bearings in arms 15, pivotally connected to the opposite uprights 1, and from the outer ends of these arms a spring yielding connection is made with the frame of the machine. As here shown, this spring yielding connection consists of a spring 16, attached at its ends to rods 17 and 18, connected, respectively, to the arms 15 and to the frame of the machine. This causes the wheel 14 to be held yieldingly against the wire fed by the 75 wheel 13.

We will now describe a means for imparting a step-by-step motion to the wheel 13, whereby the wire is fed at proper distances to properly space the crimps. 80

Extended outward from one side of the wheel 13 and equally spaced is a series of pins 19, adapted to be engaged successively by a lug 20, arranged on a lever 21, mounted to swing on a shaft or rod 22, supported in 85 the frame. A spring 23, surrounding the shaft or rod, holds the lever 21 yieldingly toward the wheel 13, so that when the lever 21 is moved in one direction the lug 20 by engaging with a pin 19 will impart a rotary 90 motion to said wheel. When the lever moves in the opposite direction to engage with a new pin 19, its inclined side will come in contact with the end of the pin first engaged, causing the lever 21 to move outward to permit it to pass. This lever at its lower end is connected by means of a link 24 with a crank 25, having its shaft-bearings in one of the uprights 2. On the outer end of the crank-shaft is a pinion 26, which engages with a 95

pinion 27, attached to a shaft 28, and also on this shaft 28 is a gear-wheel 29, which meshes with a pinion 30 on the shaft of a band-wheel 31, which is driven by any suitable motor. 5 From a crank-pin on the pinion 27 a draw-bar 32 extends to a pivotal connection with the carrier or plunger 7.

A frame 33 is adjustably connected to a projection 34, extended from one of the upper 10 rights 2, and mounted to move vertically in the outer portion of this frame 33 is a cutter-plate 35, having at its upper end a cutter-point 36. An upward motion is imparted to the plate 35 by means of a cam 37 on a cam-shaft 38, having bearings in the frame 33, and on the inner end of this shaft 38 is a crank-arm 39, from which a rod 40 extends to a connection with the outer end of a lever 41, mounted on the upright 2. From the outer 15 end of this lever 41 rods 42 43 extend, respectively, to cranks 44 45 on rock-shafts 46 47, mounted in the frame 33.

Attached to the outer ends of the rock-shafts 46 47 are cutting and bending devices, 20 here shown as segmental lugs 48 49, to operate in conjunction with the cutter-point 36 of the plate 35, and they also operate in conjunction with fingers 50 51 for bending the ends of the wires, as will be hereinafter described. The finger 50 is rigidly connected to the frame 33 at its upper edge, but the finger 51 is connected to the plate 35, so as to move up and down therewith. The plate 35 by moving down allows any-sized crimp to 25 pass without catching.

Pivotedly connected to the inner end of the lever 41 is a depending arm 52, which is provided with a notch 53 to receive a pin 54, projected outward from the draw-bar 32. A 30 toggle-link consisting of a section 55 and a section 56 connects the depending arm 52 with the frame of the machine—that is, the upper end of the section 55 is pivotally connected to the frame and the lower end of said 35 section is pivotally connected to the outer end of the section 56, while the opposite end of the section 56 is pivotally connected to the depending arm. It will be noted that this section 56 of the toggle-link is longitudinally 40 curved toward the arm 52, so that it may act as a detacher, as will be hereinafter described.

A bar 57 is mounted to slide between rollers 58 59, mounted on the frame of the machine, and attached to this sliding rod is a spring-finger 60, which engages with the outer edge of the arm 52. A trip-lever 61, pivoted on the frame of the machine, has its upper end pivotally connected to one end of 55 the slide-bar 57, and the lower end of this lever 61 projects into the line of movement of a pin 62 on the wheel 13 at the side opposite that upon which the pins 19 are placed. It may be here stated that there may 60 be as many pins 19 as desired—that is, to move the wire any desired distance for the purpose

of forming the necessary number of crimps. The pin 62, however, is only to impart motion to the lever 61 to operate the cutting and bending devices at the end of each complete 70 revolution of the wheel 13.

In operation the wire placed between the wheels 13 and 14 is fed a proper distance by means of the lever 21 engaging its lugs with the pins 19. While the lever 21 is moving in 75 the opposite direction, the plunger 7 will be moved downward, causing the die 8 to force or bend the wire into the lower die 9. Then as the plunger 7 moves upward the lever 21 will be again operated to move the wheels 13 80 and 14 through another step, after which the dies will again operate. This is continued until the proper length of wire is completed. At this time the pin 62 will come into engagement with the lower end of the lever 61, and 85 by rocking said lever the slide-bar 57 will be drawn inward, causing, through the finger 60, the arm 52 to be moved to engage the pin 54 in the notch 53, as indicated in Fig. 4. Now as the plunger 7 moves downward the arm 52 90 will of course be drawn downward, which will cause the lever 41 to be rocked, and this, by means of its connections, will rotate the shaft 38, so that the cam 37 will move the plate 35 upward to its proper position. Then 95 the rock-shafts 46 and 47 will be operated, causing the edges of the lugs 48 and 49, in conjunction with the point 36 of the plate 35, to cut off the finished length of wire from the main length. Then by a continued movement of the shafts 46 and 47 the inner curved edges of the lugs 48 and 49 will bend the ends of the wires around the fingers 50 and 51, as indicated in Fig. 8. During this forward movement of the arm 52 and before the die 100 105 8 reaches the wire the curved link-section 56 will engage with the pin 54 and push the arm 52 out of connection with the pin 54. Then a spring 63 will draw the lever 41 to its original position, and consequently move the plate 35 110 downward and return the cutting-lugs 48 and 49 to their normal position, so that a new length of wire may be crimped through before it is again cut off. The position of the machine at this time is indicated in Fig. 6. 115

To insure a throwing out laterally of a finished length of wire, we employ a discharging-finger 64, which is pivoted to the frame 33 and has its lower end extended downward at the inner side of the wire. On the upper 120 end of the finger 64 is an upwardly-swinging trip-section 65, adapted to be engaged by a pin 66 on the crank 45. When this crank 45 moves downward, the pin 66, engaging with the upper side of the trip portion 65, will 125 swing the finger 64 in such manner as to push the wire outward; but during the downward movement of said crank and after the finger 64 shall have completed its work the pin 66 will pass to the under side of the swinging 130 section 65. Then as the crank 45 moves upward the pin 66, engaging with the under side

of the swinging section 65, will swing the same upward without imparting any motion to the finger 64. (See Fig. 8.)

The severed wire is held on the finger 51 during the operation of bending the end by means of a finger 67, extended from one end of the lever 68, and from the other end of this lever 68 a rod 69 extends to a connection with the lever 41. In attaching the wire to a mattress the said wire is engaged with the springs in a line and the hook ends are engaged around the frame of the mattress.

While we have described the machine as for crimping spring holding-wires, it is to be understood that it may be used for crimping wires used in other connections, and the dies may be of various forms to produce the desired shape of crimp in the wires.

Having thus fully described our invention, we claim as new and desire to secure by Letters Patent—

1. In a machine for crimping wire, means for imparting a step-by-step feed to the wire, a die, means for imparting motion to the die, and means operating to cut the wire in lengths and to bend the ends thereof, substantially as specified.

2. In a wire-crimping machine, a vertically-movable crimping-die, means for moving the wire through said die, means for operating the die, radial cutting devices for severing the wire, and fingers coacting with said cutting devices for forming hooks at the ends of the wire, substantially as specified.

3. In a wire-crimping machine, a feeding-wheel, a swinging lever adapted to engage successively with pins extended from one side of said wheel, whereby an intermittent rotary motion is imparted to the wheel, a vertically-movable die, and means for imparting motion to the die, substantially as specified.

4. In a wire-crimping machine, an upper and lower die, means for imparting a vertical motion to the upper die, means for feeding wire to the die, and rocking guides for the wire at opposite sides of the lower die, substantially as specified.

5. In a wire-crimping machine, an upper die, a lower die, the upper die being movable and the lower die stationary, means for feeding wire to the die, guides for the wire on opposite sides of the lower die, and cutting and end-turning devices forward of the die, substantially as specified.

5. In a wire-crimping machine, a crimp-forming die, means for imparting motion to the same, rock-shafts forward of the die, cutting and bending lugs on the outer ends of said shafts, means for rocking the shafts, a plate having a cutting-point for coacting with the cutting-lugs, and fingers coacting with the cutting-lugs for bending the ends of the wire, substantially as specified.

7. In a wire-crimping machine, a feeding-wheel, a series of pins extended from one side of said feeding-wheel, a swinging lever for en-

gaging with said pins to impart motion to the wheel, means for swinging said lever, a vertically-movable crimping-die, and means controlled by the feeding-wheel for cutting a wire 70 and also for forming hooks at its ends, substantially as specified.

8. In a wire-crimping machine, a feeding-wheel, a series of pins extended from one side of said feeding-wheel, a swinging lever for engaging successively with said pins and imparting motion to the wheel, means for swinging said lever, a vertically-operating die, means for moving said die, cutting and bending devices forward of the die, a lever mounted to swing on the frame of the machine and adapted to operate the cutting and bending devices, a trip-lever, a pin extended from the feeding-wheel for engaging with the trip-lever, and means controlled by said trip-lever 80 to swing the first-named lever, substantially as specified.

9. In a wire-crimping machine, the combination with a crimping-die, of a vertically-movable plate having a cutting-point, rock-shafts, cutting-lugs connected with said rock-shafts and coacting with the cutting-point, means for rocking the rock-shafts and also operating to move the point-bearing plate vertically, substantially as specified. 95

10. In a wire-crimping machine, the combination with a crimping-die and means for operating the same, of rock-shafts, cutting-lugs on said rock-shafts, means for rocking the rock-shafts, a cutter-point-carrying plate 100 coacting with the lugs, a discharging device for a severed length of wire, and means for operating the same, substantially as specified.

11. In a wire-crimping machine, a feeding-wheel, means for imparting a step-by-step rotary motion to said wheel, a driving-gear, a vertically-movable die-carrier, a rod connecting said carrier with the driving-gear, a pin extended outward from said rod, a lever pivoted on the frame of the machine, an arm depending from the inner end of said lever and having a notch to receive the pin, a toggle-link connection between said arm and the frame of the machine, the lower link being curved to engage with the pin whereby the 115 arm may be separated from the pin, and cutting devices operated by said lever, substantially as specified.

12. In a wire-crimping machine, a wire-feeding device, a vertically-movable crimping-die, a driving-gear, connections between the driving-gear and the die whereby motion is imparted to the die, guides for the wire to be crimped, the said guides to be mounted to rock, a vertically-movable plate having a cutting-point, a finger supported on said plate, a device for holding a wire down on said finger, a fixed finger opposite the first-named finger, and rocking cutters coacting with the first-named cutter to sever a wire and also co- 125 acting with the fingers to bend the ends of a wire, substantially as specified. 130

13. In a wire-crimping machine, a driving mechanism, a feed - wheel operated by the driving mechanism, a die - carrier movable vertically in guides, connections between the carrier and the driving mechanism, rock-shafts, means for imparting motion to the rock-shafts, cutting-lugs extended from said rock-shafts, a vertically-movable plate having a cutting-point coacting with the cutting-lugs, means for moving said plate upward, a fixed finger adjacent to the end of one of the

rock-shafts, a finger carried by the point-carrying plate, a device for holding wire down on the last-named finger, and means for ejecting the severed wire, substantially as specified. 15
